UNITED STATES PATENT OFFICE.

SOLOMAN E. OVIATT, OF RICHFIELD, OHIO.

IMPROVEMENT IN WAGONS.

Specification forming part of Letters Patent No. 173,417, dated February 15, 1876; application filed March 4, 1875.

To all whom it may concern:

Be it known that I, S. E. OVIATT, of Richfield, in the county of Cuyahoga and State of Ohio, have invented new and useful Improvements in Wagons, of which the following is a full and complete description, reference being had to the accompanying drawings making a part of this specification, in which—

Figure 1 is a plan view of the wagon-gear. Fig. 2 is a side view. Fig. 8 is a front view. Figs. 10 and 12 are detached sections.

Like letters of reference refer to like parts in the several views.

The nature of this invention relates to a wagon-gear, the construction and arrangement of which are as follows:

The invention referred to consists in connecting the front and hind axle-trees to each other by means of two rails, A, Fig. 1. The front ends of the rails are attached firmly to the bolster B of the front axle-tree C, whereas the hind ends of the rails are secured to both the bolster and axle-tree B' and C', partially in each, gains being cut in the bolster and axle-tree, forming a mortise, through which the rails pass, as shown in Figs. 1 and 2, and in which mortises they are free to slide endwise, for lengthening or shortening the distance of the hind and front wheels from each other. D, Fig. 1, is a collar, provided with a flange, E, a detached view of which is shown in Fig. 10. Said collar is secured to the bolster and axle-tree by the flange which is bolted thereto, as shown in Fig. 1, so that the rail may pass through both the collar and axle-tree. The purpose of the collar is to strengthen the connection of the rail with the axle-tree, and whereby the same may be secured thereto by a pin, a, Fig. 2. In practice, both rails are provided with a collar.

The pole or tongue L of the wagon is attached to the axle-tree by a bolt, b, Fig. 1, passing through the eye-pieces or ears c c, and is much longer than the thickness of the pole in connection therewith. On the bolt, on each side of the pole, is a spring, N. The purpose of the long bolt and the springs is to prevent the outer end of the pole from swaying so much laterally as to strike the shoulders of the horses, or to draw too severely on the col-

lars and neck-yoke straps, which, as poles are usually attached, they are very liable to do, especially when the wagon is passing over rough roads.

It will be obvious that, as the pole of the wagon in its attachment to the axle-tree is allowed a lateral movement on the bolt b, the swaying of the pole at the outer end will be less than if the pole had no such lateral movement allowed to it; hence the jerking and straining upon the team will be very much lessened.

The tendency of the springs is to keep the pole straight in its relation to the wagon, and to prevent it from striking with too much force on the ears c c, holding the bolt. The pole is braced in its connection with the axle-tree by the draw-rods O O, attached to the axle-tree, and hooked into the ears d of the rub-iron or plate P. Said plate embraces the top and sides of the pole, an end view of which is shown in Fig. 12. The plate, in consequence of its embracing the sides of the pole, adds to its strength, thereby compensating for its weakness caused by the bolt-hole.

What I claim as my invention, and desire to secure by Letters Patent, is—

1. The combination of the extension-rails A, fixed in the front bolster B, and sliding in the bolster B' and axle-tree C', with devices for securing said rails to the bolster and axle-tree at various points of extension along said rails, substantially as described, and for the purpose set forth.

2. The collar D, provided with a flange, E, in combination with an adjustable or extension rails, A, bolster B', and axle-tree C', as and for the purpose set forth.

3. The eye-piece or ears c c, bolt b, and springs N N, in combination with the pole L and axle-tree C, substantially in the manner as described, and for the purpose specified.

4. The combination of the pole L, plate P, draw-rods O O, and axle-tree C, in the manner as described, and for the purpose specified.

SOLOMAN E. OVIATT.
